[57] **CLAIM**

The ornamental design for a water refrigeration and dispensing unit, as shown and described.

DESCRIPTION

FIG. 1 is a front elevational view of a water refrigeration and dispensing unit showing my new design;
FIG. 2 is a right side elevational view thereof;
FIG. 3 is a rear elevational view thereof;
FIG. 4 is a top plan view thereof;
FIG. 5 is a top, front, and left side perspective view thereof; and
FIG. 6 is a bottom plan view thereof.

FIG. 1

FIG. 2

FIG. 3

FIG. 4
